US00D991986S

(12) **United States Design Patent** (10) **Patent No.:** **US D991,986 S**
(45) **Date of Patent:** **** Jul. 11, 2023**

(54) **BUCKET SHROUD**

(71) Applicant: **Caterpillar Inc.**, Peoria, IL (US)

(72) Inventors: **Nathan Bjerke**, Peoria, IL (US);
Thomas Marshall Congdon, Dunlap, IL (US)

(73) Assignee: **Caterpillar Inc.**, Peoria, IL (US)

(**) Term: **15 Years**

(21) Appl. No.: **29/834,037**

(22) Filed: **Apr. 8, 2022**

Related U.S. Application Data

(63) Continuation of application No. 29/785,347, filed on May 25, 2021, now Pat. No. Des. 952,697, which is a continuation of application No. 29/708,298, filed on Oct. 4, 2019, now Pat. No. Des. 927,561.

(51) **LOC (14) Cl.** **15-03**

(52) **U.S. Cl.**

USPC **D15/29; D15/28**

(57) **CLAIM**

The ornamental design for a bucket shroud, as shown and described.

DESCRIPTION

FIG. 1 is a perspective view of a bucket shroud showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.

The dot-dash broken lines illustrate boundaries which form no part of the claimed design.

1 Claim, 5 Drawing Sheets
